IRONER CABINET (HORIZONTAL PIVOT)

Henry W. Altorfer, Peoria, Ill.

Application July 13, 1936, Serial No. 90,375

3 Claims. (Cl. 312—25)

This invention relates to the cabinet enclosure for a domestic ironing machine.

Because housewives prefer to iron in upstairs rooms rather than in the basement, and the ironer must be stored a large part of the time, a cabinet or enclosure is almost necessary to keep the ironer clean and free of dust. The height of the ironer cabinet, when the cover is put over the ironer in normal position, is considerably higher than normal table height and this makes the ironer awkward to store and detracts from its utility as an occasional table.

The main object of this invention is to provide an ironer that will be of proper height for convenient use as an ironer, yet when closed and covered will be of considerably lower height to enhance its usage as a table.

Another object is to improve the proportions of the cabinet, when closed, by reducing the height in proportion to the width.

A still further object is to provide a structure or mechanism that is simple and easy to operate and further is both quiet and sturdy.

Other objects and benefits will be disclosed by examination of the following drawings and descriptions of which:

Fig. 1 is a front elevational view of the ironer stored in the cabinet, and

Fig. 2 is a plan view of Fig. 1.

Fig. 3 is a front sectional view in elevation with the ironer in operating position and with the cover swung back, and

Fig. 4 is a plan view of Fig. 3, and

Fig. 5 is an end elevational view with parts broken away to show the operating mechanism in relation to the cover which is in the open position, and

Fig. 6 is an end elevational view with the cover closed and showing the ironer in its lowered position in dotted outlines, and

Fig. 7 is an enlarged sectional view in plan, taken on the line 7—7, Fig. 6, showing one of the horizontal pivot members, and

Fig. 8 is an enlarged sectional view in plan, taken on the line 8—8 of Fig. 6, showing the arrangement of the vertical slide members.

I designate the lower cabinet as a unit 10 and the cabinet cover as 11. The ironing machine as a unit is designated 12 and the slideable table as 13. It will be noted that the cabinet 10 is supported on two hollow legs which form wells in which the operating mechanism is enclosed.

The slideable table 13 is supported by two vertical slide arms 14 gibbed in slide brackets 15

which are securely riveted to the lower cabinet 10.

Riveted to the bottom of the slides 14 are the spring arms 16 with the groove pins 17 attaching in tension the balance springs 18 by the adjustable eye bolts 20 and the brackets 19 which are riveted to the lower cabinet 10.

The hinge arm 21 is bolted to the stiffener member 22 which is riveted to the cabinet cover 11.

The hinge arms 21 are securely attached to the hinge shafts 23 by set screws and these hinge shafts pivot in the hinge brackets 24 bolted to the lower cabinet 10.

On the other ends of the hinge shafts 23, and securely attached thereto by set screws, are the crank arms 25. Pivoted connecting the arms 25 with vertical arms 14 are the connecting links 26.

The rubber bumpers 27 riveted to the sliding table 13 soften and quiet the stop of the table 20 against the inner flange of the cabinet 10.

Now having described the parts and their relations to one another, I will now describe the operation of my ironer cabinet.

With the ironer closed as in Fig. 1, it will be noted that the cabinet top is considerably lower than it would be normally, by the fact that the slideable table 13, carrying the ironer, is much lower than the arched opening in the lower cabinet.

To open the ironer, the operator merely lifts the cabinet top which pivots on its hinge and raises the ironer table in the end slides by the connecting links. This operation is assisted by the balance springs when the cabinet top is on the inside center of the hinge but as soon as the cabinet cover is on the other side of the hinge, its weight balances against the weight on the sliding table becoming progressively more effective as it pivots on the hinges until when completely open, the weight of the cabinet top holds the table and ironer securely in the open position.

The closing operation is the reverse of the foregoing and will not be described in detail.

It will be understood that there are numerous optional structures and that I do not desire to be limited to the exact structure I have described.

I now claim as new:

1. An ironing machine cabinet comprising, a housing of generally inverted U-shape, the legs 50 of the U being hollow and providing machinery wells, an ironing machine support disposed horizontally within the vertical bounds of the housing and vertically movable therein between upper and lower limits, a pair of guide members, one 55

guide member being secured within each leg well, a vertically movable slide member in each guide member, each slide member being rigidly secured at its upper end to said support, a pair of horizontal pivot members, one pivot member being secured adjacent to each leg and within the housing and below the top thereof, a pair of levers, each lever being pivoted intermediate its ends upon one of said pivot members, said levers having one end of each projecting rearwardly exterior of the housing, a cover member having its rearward edge secured to said projecting lever ends, and links connecting the other ends of said levers and the lower ends of said slide members.

15 2. An instrument housing cabinet comprising an inverted substantially U-shaped structure having hollow legs constituting supports for the middle portion and providing wells for operating mechanism, said middle portion presenting an opening to receive an instrument support, an instrument support disposed normally below and spaced from said middle portion, downwardly projecting supporting arms mounted upon the ends of said support and projecting into said wells, guides mounted in the latter and engaged with said arms of said support to render the latter movable vertically only, a pair of levers each projecting at one end into one of said wells and

having operative connection at said ends with said arms of said support and pivotally secured between their ends to the rear edge portion of the middle of said U-shaped structure, and a cover for the latter rigidly secured along its rear edge to the other ends of said levers and constituting a manually engageable means for operating said levers to cause said support to be raised as said cover is raised and vice versa.

3. In a cabinet for a domestic ironer, a table 10 substantially lower than normal table height having hollow legs for housing operating mechanism and a central opening for an ironer base, an ironer base supported for vertical movement on arms guided in slide brackets in the hollow legs, an ironer mounted on the base, a cabinet cover pivotally mounted on the table by hinged arms, and mechanism including hinged arms of the cabinet cover co-acting with the support arms of the base whereby the ironer may 15 be raised for normal operation above the low table by opening swinging movement of the cabinet cover and by reverse closing movement lowered below the table, the cabinet top of the cover being at approximately normal table height 20 in closed position.

HENRY W. ALTORFER.
